(57) **CLAIM**

The ornamental design for a mobile personal computer, as shown and described.

DESCRIPTION

FIG. 1 is a perspective view of a mobile personal computer showing our new design with the keyboard in an in use position;

FIG. 2 is a front view thereof;

FIG. 3 is a rear view thereof;

FIG. 4 is a left side view thereof;

FIG. 5 is a right side view thereof;

FIG. 6 is a top view thereof; and

FIG. 7 is a bottom view thereof.

FIG. 8 is a perspective view thereof but with the keyboard in the back position;

FIG. 9 is a front view thereof;

FIG. 10 is a rear view thereof;

FIG. 11 is a left side view thereof;

FIG. 12 is a right side view thereof;

FIG. 13 is a top view thereof; and,

FIG. 14 is a bottom view thereof.

The broken lines shown in the drawings are for illustrative purposes only and do not form part of the claimed design.
